UNITED STATES PATENT OFFICE.

WILLIAM A. BUTCHART, OF DENVER, COLORADO.

CONCENTRATOR.

1,111,992.

Specification of Letters Patent. Patented Sept. 29, 1914.

Application filed November 23, 1913. Serial No. 803,641.

To all whom it may concern:

Be it known that I, WILLIAM A. BUTCHART, a citizen of the United States, residing at Denver, in the county of Denver and 5 State of Colorado, have invented a new and useful Concentrator, of which the following is a specification.

This invention relates to concentrators of the reciprocating table type and more particularly to an improvement in the concentrator disclosed in the United States Patent No. 997,235, granted to me July 4th, 1911, in which riffles are placed upon the table in such manner that its surface is divided by 15 deflections of the riffles into three distinct zones, whose respective functions are stratification, cleaning and discharge of finished product or concentrate.

The main object of the present invention 20 is to increase the effectiveness of concentration and cleaning and to increase the capacity of the concentrator of the above described type. The greater efficiency is obtained by forming the riffles in such manner 25 that in one or more of these zones they gradually decrease in height from the upper toward the lower side of the table. This graduation in the height of the riffles may be distributed uniformly so that each riffle is 30 slightly lower than the riffle next above it on the table, or the gradation may take place by steps, the riffles being arranged in a series of groups of progressively decreasing height.

35 Other objects of the invention will appear hereinafter.

The accompanying drawings illustrate an embodiment of my invention, and referring thereto: Figure 1 is a plan view of a concentrator embodying my invention. Fig. 2 is a section on line x^2-x^2 in Fig. 1. Fig. 3 is a section on line x^3-x^3 in Fig. 1. Fig. 4 is an elevation of one of the riffles. Fig. 5 is a transverse section of a table showing a 45 modified concentrator. Fig. 6 is an elevation of one of the riffles shown in Fig. 5. Fig. 7 is a transverse section of a modified form of table. Fig. 8 is a plan view of another modification.

50 1 designates a concentrator table supported on suitable means 2 for permitting reciprocating longitudinal motion thereof by head motion 3 adapted to impart to the table a differential reciprocation so as to produce 55 a tendency for the material on the table to move from the feed end a to the delivery end

b of the table. The table is supported in inclined position so that one edge c is somewhat higher than the opposite edge d , and may be also inclined somewhat longitudinally so that the delivery end b is slightly higher than the receiving end a . An end board 4 is provided at the receiving end for retaining the material on the table. At the upper or feed side of the table and at the 60 receiving end is provided a feed box 5 of any suitable construction adapted to receive the material to be concentrated together with feed water, and to distribute it over the receiving end of the table at the upper side 65 thereof. A water box 6 for dressing water is also provided at the upper side of the table. The surface of the table 1 is approximately a plane and is formed in any suitable manner for receiving the material, 70 for example, of wood covered with linoleum. On the surface of this table are secured a series of riffle strips 7. In the form of the invention shown in Figs. 1 to 3 these riffle strips 7 are longitudinally tapered continuously from the feed receiving to the concentrates delivery end. The initial portions 7^a of the riffles preferably extend longitudinally of the table parallel to the line of reciprocation or approximately so, the area occupied by these riffle portions constituting a 75 stratifying zone. Along a certain line $e-e$ extending preferably diagonally of the table from near the feed box to a point adjacent to the lower corner at the concentrates discharge end, the riffles 7 are deflected upwardly as shown at 9. The portion of the table occupied by these upwardly deflected sections 7^b of the riffles constitutes the cleaning zone. These upwardly deflected portions terminate along a line $f-f$, also preferably extending diagonally across the table, the riffles being again deflected at this line, toward the concentrates discharge end, and from this line of deflection $f-f$, extending 80 85 rectilinearly approximately parallel to the line of reciprocation as shown at 7^c, the area occupied by these riffle portions 7^c being the concentrate discharge zone. Near the concentrates discharge end of the table 90 the riffles are again deflected upwardly as shown at 7^d for the purposes hereinafter set forth.

In Fig. 2 the riffles 7 are shown as of progressively decreasing height from the upper 110 to the lower side of the table. By reason of this graduation in height and of the

longitudinal taper of the riffles in conjunction with the diagonal arrangement of the cleaning zone, it follows that the riffles in the cleaning zone present a gradual decrease 5 in height from the upper to the lower riffle, which is more rapid than the decrease in height transversely of the other zones. I have found that it is necessary in order to secure full capacity in concentration and 10 efficiency in cleaning, that the width of the interriffle channels be properly proportioned to the height of the riffles, so that the cross sectional form of the interriffle channels may be approximately the same at all points upon 15 the table. To accomplish this the thicker riffles toward the upper side of the table are placed farther apart than the thinner riffles toward the lower side thereof, the distances between the riffles decreasing progressively 20 from the upper to the lower side of the table.

The operation is as follows: Material to be concentrated is supplied to the feed box 5 and is distributed upon the table by the accompanying feed water. As the material 25 passes over the table it is intercepted by the riffles 7, and the differential longitudinal reciprocation of the table causes the material to become stratified, with concentrates at the bottom of each interriffle channel, and 30 at the same time to advance from the receiving toward the delivery end in well known manner. As the material thus advances it is subjected to the action of dressing water flowing across the table from the 35 dressing water box 6. Upon reaching the deflected riffle sections in the cleaning zone, the material is subjected to additional influences: 1st.—A rearward flow of dressing water along the inter-riffle channels, the direction of flow being the reverse of that 40 which the material is moving, and 2nd.—A vanning action or "side-shake" caused by the riffles in the cleaning zone not being parallel to the line of table reciprocation. 45 By these means the sand or gangue matter is brought to the surface, washed backward and out of the cleaning zone by the dressing water, passes successively over the riffles and is discharged at the tailings side of the table. 50 The clean concentrates pass into the delivery zone between the riffle portions 7^c and are guided thereby to the delivery end of the table where they are discharged into any suitable receptacle. As the riffle portions 7^c 55 are frequently of considerable thickness (e. g. 3/8" to 3/4"), it is evident that water passing on to the table from the water box 6 will be entirely carried away by the upper riffles, the greater portion escaping over the 60 concentrates discharge end, and that the lower riffles will thus be deprived of the necessary dressing water. The upward deflections 7^d at the delivery end of the table retain water in the interriffle channels, 65 thereby maintaining the mobility of the ma-

terial therein, and causing an ample supply of water to flow across the table to the lower riffles.

The removal of silica or gangue matter is effected largely in the cleaning zone above 70 described, between the lines *e*—*e* and *f*—*f*, and it is in this zone more particularly that the gradual decrease in height of the riffles from the upper to the lower side of the table is most essential, since it is in this zone 75 that the concentrates tend to accumulate and overload the upper riffles. Hence the desirability of deep channels between the upper riffles to remove a large proportion of the concentrates and prevent them from 80 passing to the lower part of the table. Such arrangement of the upper riffles results in a comparatively small amount of concentrates reaching the lower part of the table, where relatively low riffles are consequently provided in order to effectively clean the concentrates therein. The initial cleaning effect, however, is produced in the stratifying zone concurrently with the stratification, and a transversely graduated decrease in 85 height of the riffles in such zone is also desirable in some cases. Inasmuch as the amount of concentrates delivered decreases in general from the upper to the lower side of the table, this gradation in the height of 90 the riffles is also of advantage in the delivery zone. The construction shown in Figs. 2 and 3 provides for such transverse gradation of height of the riffles in the stratifying zone, in the cleaning zone and also in 95 the delivery zone, since each riffle is of less height than the one next above it throughout its length. The advantage of the graduation in width of the interriffle channels will 100 be apparent on reference to Fig. 2 wherein the dotted lines drawn horizontally from the upper edges of the riffles indicate the overflow level for each riffle. It is clear that to secure the maximum carrying capacity of each interriffle channel its width 105 should be proportionate to the height of the riffle at the lower side thereof, and therefore the width of the channel should be determined by the height of the adjacent riffles.

The height of the riffles may be graduated 110 progressively as above described, or in steps, as shown in Fig. 5, each step consisting of a group of riffles of equal height throughout the group, but of greater height than the 115 riffles in the group next lower on the table, and as shown in Fig. 6, the riffles may be untapered or of uniform height from end to end, the transverse decrease in depth of the interriffle channels in the several zones being in that case produced solely by the 120 transverse graduation in the height of the riffles themselves. On the other hand, as 125 shown in Fig. 7, the riffles may be all of uniform height from side to side of the table, but tapering longitudinally, as in Fig. 4, so 130

that by reason of the diagonal arrangement of the cleaning zone, the portion 7^b of the riffle in the cleaning zone will occur in a relatively thick or high portion of the riffles 5 near the feed end and in progressively thinner or lower portions toward the discharge end of the table, the longitudinal taper of the riffles, in conjunction with the oblique arrangement of the cleaning zone, producing 10 a progressive decrease in the height of the riffles in the cleaning zone.

By arranging progressively decreasing heights of riffles from the upper toward the lower side of the table, as shown in Fig. 15 2 or Fig. 5, it is evidently possible to cause the cleaning zone to cross the table at right angles as shown in Fig. 8, instead of diagonally thereof, while still retaining the desired features of successively diminishing 20 riffle thicknesses therein.

It should be understood that the lines $e-e$, $f-f$, may occur at other locations than those here shown, and that if both be moved rearwardly of the table surface and somewhat more widely separated, the initial 25 portions 7^a may be in whole or in part suppressed, the stratification and cleaning zones being thus wholly or partially merged. Or the line $f-f$ may be moved toward the concentrate discharge end, so as to eliminate 30 if desire the delivery zone 7^c .

What I claim is:

1. A reciprocating concentrator table having a transversely inclined plane surface, feed and wash water supply means at the upper side of said surface, and riffles extending longitudinally on said surface and having portions thereof deflected toward the upper side of the table to provide 35 a cleaning zone, the riffle portions in said cleaning zone being of greater height at the upper part than at the lower part of said zone.

2. A reciprocating concentrator table having a transversely inclined plane surface, feed and wash water supply means at the higher side of said surface, tapering riffles extending longitudinally thereon, the height of said riffles decreasing toward the concentrates discharge end of said surface, said 45 riffles having portions deflected toward the higher side of said table to form a cleaning zone, said cleaning zone extending diagonally of the table, the deflected riffle portions in said cleaning zone being of progressively decreasing heights toward the lower part of said cleaning zone.

3. A reciprocating concentrator table having a transversely inclined plane surface, 50 parallel riffles on said surface forming parallel spaces, or interriffle channels decreasing in width from the higher or feed and wash water side of said surface toward the tailings discharge side thereof.

4. A reciprocating concentrator table hav-

ing a transversely inclined plane surface, parallel riffles on said surface consisting of strips decreasing in height from the higher or dressing water side thereof toward the lower or tailings discharge side of said surface, said riffles separated by parallel channels progressively decreasing in width from the higher or feed and wash water side of said surface toward the lower or tailings discharge side thereof. 70

5. A reciprocating concentrator table having a transversely inclined plane surface, riffles thereon decreasing in height above said surface from the higher toward the lower side thereof, said riffles being deflected first toward the higher or wash water side of said table and then toward the concentrates discharge end thereof, said deflections occurring in the respective riffles at 80 points which will produce a continuous zone 85 of deflected riffle portions extending from the higher toward the lower side of said table and the height of the riffles in said zone progressively decreasing toward the lower part of the zone. 90

6. A reciprocating concentrator table having a transversely inclined plane surface, riffles thereon tapering or diminishing in height from the feed receiving end of said table to the concentrates discharge end 95 thereof, said riffles being at certain points deflected first toward the higher or wash water side of said table and then toward the concentrates discharge end thereof, said deflections occurring at such points in the 100 respective riffles as will produce a zone of tapering deflected riffle portions extending across said table in a diagonal direction in such manner that said deflected tapering 105 riffle portions decrease in their respective heights from the higher toward the lower or tailings discharge side thereof.

7. A reciprocating concentrator table having a transversely inclined plane surface, riffles thereon extending substantially the 110 full length thereof, the course of said riffles being deflected three times, the first and third of said deflections being toward the higher or feed and dressing water side of the table, the third separated from the second by straight riffles, the third deflection 115 terminating at the concentrates discharge end of the table.

8. A reciprocating concentrator table having a transversely inclined plane surface, 120 provided with channels extending substantially from end to end thereof, the course of said grooves or channels being three times changed or deflected, the first deflection being toward the higher or dressing water side of said table, the second deflection being in a direction the reverse of the first, and the third deflection being in substantially the same direction as the first. 125

9. A reciprocating concentrator table hav-

ing a transversely inclined plane surface, riffles on said surface consisting of strips decreasing in height from the higher or dressing water side thereof toward the lower or tailings discharge side of said surface, said riffles separated by channels decreasing in width from the higher toward the lower side thereof, said riffles having portions thereof deflected toward the upper side of the table to constitute a cleaning zone, the riffle portions in said cleaning zone being of greater height at the upper

part than at the lower part of said table, and said riffles having upwardly deflected portions terminating at the concentrates discharge end of the table. 15

In testimony whereof, I have hereunto set my hand at Morenci, Arizona, this 22nd day of November, 1913.

WILLIAM A. BUTCHART.
